UNITED STATES PATENT OFFICE.

FREDERICK M. FURBER, OF REVERE, MASSACHUSETTS.

SPARK-PLUG.

1,199,540.

Specification of Letters Patent. Patented Sept. 26, 1916.

Application filed July 12, 1915. Serial No. 39,337.

To all whom it may concern:

Be it known that I, FREDERICK M. FURBER, a citizen of the United States, residing at Revere, in the county of Suffolk and State 5 of Massachusetts, have invented certain Improvements in Spark-Plugs, of which the following description, in connection with the accompanying drawings, is a specification, like reference characters on the drawings indicating like parts in the several 10 figures.

This invention relates to spark plugs of the character commonly used in internal combustion engines and has particular reference to a spark plug of the general type 15 shown in my prior Patent No. 1,126,974, granted February 2, 1915. The spark plug shown in this patent comprises an outer shell or body provided with a gradually tapered bore and an insulator which is secured in said body by a soft, metal bushing that 20 engages frictionally the outer surface of the insulator and the wall of said bore and is shaped to compensate for the variations in 25 shape between the insulator and the bore. According to the preferred method of making this plug the bushing is forced on to the insulator, thus causing it to conform to the surface of the insulator, and the outer 30 surface of the bushing is then turned down to fit the seat formed for it in the bore of the body. This construction has proved exceedingly satisfactory and because of its extreme simplicity can be manufactured very 35 economically.

The present invention aims to improve the construction shown in the patent above designated with a view particularly to effecting a further economy in manufacture.

40 The invention will be readily understood from the following description, reference being made to the accompanying drawings, in which—

Figure 1 is a vertical, sectional view 45 through a spark plug showing one step in the process of manufacture; Fig. 2 is a view similar to Fig. 1, showing a further step in the process of manufacture; Fig. 3 is a vertical sectional view through a completed 50 spark plug constructed in accordance with this invention; and Fig. 4 is a view in side elevation of the plug shown in Fig. 3.

Referring now to the drawings, 2 indicates the shell or body of the plug which 55 preferably is made from bar stock of hexagonal cross section by turning off to the

desired diameter the lower part of a piece of stock of the required length and threading this reduced part as indicated at 4. The body is then drilled and reamed to form 60 a bore 6 which preferably is made cylindrical in shape from the lower or inner end of the body (referring to its normal position) to a point slightly above the reduced portion and is then tapered gradually from this 65 point to the outer end of the body. This taper preferably is made very gradual and is of the character sometimes termed a "sticking" taper. This body is substantially 70 like that shown in the patent above designated.

The insulator 8 may be constructed substantially like that shown in the patent above referred to but preferably is provided just below its middle with an enlargement 75 9, thus providing a shoulder 10 at the lower end of said enlargement and a shoulder 11 above it. The portion of the insulator above the part 9 preferably is tapered to conform to the tapered bore of the body 2. A series 80 of gaskets 12 encircle the tapered part of the insulator and are fitted so tightly in the tapered portion of the bore of the body that their frictional engagement between the body and insulator holds the insulator 85 securely in its operative position. The copper-asbestos gaskets readily obtainable on the market may be conveniently employed for this purpose. These gaskets each consists of a ring of thin copper approximately 90 circular in cross section, as shown in Fig. 1, provided with a core of asbestos. In manufacturing the plug, a series of these gaskets are strung on the tapered part of the insulator, as shown in Fig. 1, and the 95 insulator is then inserted in the body 2. These gaskets, of course, are smaller in diameter than either the outer end of the bore 6 or the tapered part of the insulator 100 adjacent to the enlargement 9. Consequently they will tend to hold the insulator in substantially the position in the body in which it is indicated in Fig. 1. The plug is now placed in a die 14 having a hole 105 formed therethrough to receive the upper end of the insulator, this hole being of a diameter slightly smaller than that of the outer-end of the bore 6. Another gasket 15, like the gaskets 12, is placed on the end of the insulator below the shoulder 10. While 110 the plug is supported in an inverted position in the die 14, as shown in Fig. 2, a hol-

low sleeve like plunger 16 is brought down into the cylindrical part of the bore of the body and presses the gasket 15 against the shoulder 10 and forces the insulator 8 and 5 the gaskets 12 into the tapered part of the bore into substantially the positions shown in Figs. 2 and 3. During this movement the upper shoulder 11 on the insulator engages the lowermost gasket 12 and transmits to the series of gaskets the longitudinal 10 movement of the plunger, while the movement of the larger portion of the tapered part of the insulator into a smaller part of the tapered portion of the bore compresses 15 the gaskets laterally and flattens them out, forcing them to completely fill the space between the insulator and the body and to conform to the differences in shape between the tapered surfaces of the insulator and bore. The die 14 prevents the forcing of the 20 gaskets out of the bore of the body although obviously the upper end of the body could be provided with an inturned lip or flange that would perform this function. Since 25 these gaskets are made of a soft metal and have a yielding core they conform readily to the differences in shape between the surface of the insulator and the tapered wall of the bore. Sufficient pressure is used on 30 the plunger 16 to force the insulator and gaskets into the body so firmly that the insulator cannot be unseated without employing pressures exerted inwardly on the insulator very much in excess of those to 35 which it is subjected while in use. In other words, the frictional engagement of the gaskets 12 with the insulator and body maintains the insulator in its operative position. The gasket 15 is employed simply 40 for the purpose of protecting the shoulder 10 of the insulator from being crushed by the end of the plunger 16.

It is obvious that this construction avoids 45 the necessity for the machine work required in the manufacture of the plug of my prior patent to fit the insulator bushing to its seat in the body. It also avoids one of the pressing operations, namely, that required to force the bushing on to the insulator. 50 The construction provided by this invention is of further advantage in producing a tighter joint between the insulator and body than could be obtained in the construction shown in the patent. The tapered surfaces of 55 the insulators are so irregular that it is not always possible to produce a tight joint between the bushing and the insulator itself. In the present construction, however, the gaskets 12 each conforms independently of 60 the others to the cross sectional area of the annular space in which they are confined between the insulator and bore. The shape of 65 this space varies at successive points along the insulator due chiefly to the warping of the insulator in its process of manufacture 70

but the gaskets, being independent of each other, adjust themselves individually to the space into which they are crowded by the pressure applied to the plunger 16. This fact results in effecting a much firmer contact between the gaskets and the insulator than would be possible with a single piece of soft-metal of even a much greater length than the length of the entire series of gaskets and it produces a joint between the insulator and body that is tight even after long use and at very high temperatures. 75

If desired, a short sleeve 18, preferably made of steel or of the material from which the body 4 is made, can be forced into the cylindrical part of the bore 6, as shown in Fig. 3, until it bears against the gasket 15 where it will serve as an additional means for resisting the backward movement of the insulator. When this member is to be used 80 it should be made very slightly larger in diameter than the diameter of the bore; its upper edge should be beveled on the outside; and it should then be forced into the bore by the plunger 16. Ordinarily this sleeve will 85 not be necessary but it can be used where a particularly substantial construction is desired. 90

Having thus described my invention, what I claim as new and desire to secure by Letters Patent of the United States is:— 95

1. In a spark plug, a body having a bore gradually tapered toward one end, an insulator positioned in said bore and having a part tapered in the same direction as said bore, and a plurality of gaskets encircling the tapered part of said insulator and seated in the tapered portion of said bore, said gaskets operating through their frictional engagement with said insulator and said body as the sole means for holding the insulator in the body. 100

2. In a spark plug, a body having a bore gradually tapered toward one end, an insulator positioned in said bore and having a part tapered in the same direction as said bore, and a plurality of metallic gaskets interposed between the tapered part of said insulator and the tapered portion of said bore and operating through their frictional engagement with said insulator and body to hold the insulator in the body. 110

3. In a spark plug, a body having a bore formed therethrough, said bore having a portion gradually tapered toward the outer end of the body, an insulator positioned in said bore and having a part tapered to correspond to the taper of said bore and having an enlarged portion below said taper, a plurality of gaskets independent of each other encircling the tapered part of said insulator and filling the space above said enlargement between the tapered surface of the insulator and the tapered bore of the body, said insulator being supported in said body solely 115 120 125 130

by the frictional engagement of said gaskets with the insulator and the bore of the body.

4. In a spark plug, a body having a bore gradually tapered toward its outer end, an insulator positioned in said bore and having a part tapered in the same direction as said bore, a plurality of gaskets independent of each other encircling the tapered part of said insulator and seated in the tapered portion 10 of said bore, each of said gaskets having a soft metallic shell and an asbestos core, said gaskets operating through their frictional engagement with said insulator and body to hold the insulator in the body.

5. In a spark plug, a body having a bore formed therein and provided with a seat gradually tapered toward one end of the body, an insulator positioned in said body and having a surface tapered in the same direction as said seat and having a shoulder below said surface, a plurality of gaskets encircling the tapered part of said insulator and operating through their frictional engagement with said insulator and said body 25 to hold the insulator in the body, and a

metal sleeve fast in said bore immediately below said shoulder.

6. In a spark plug, a body having a bore formed therethrough, said bore having a portion gradually tapered toward the outer 30 end of the body, an insulator positioned in said bore and having a part tapered to correspond to the taper of said bore and having an enlarged portion below said taper, a plurality of gaskets independent of each 35 other encircling the tapered part of said insulator and filling the space above said enlargement between the tapered surface of the insulator and the tapered bore of the body, said gasket serving to maintain the 40 insulator in the body through their frictional engagement with the tapered surfaces of the insulator and body, another gasket positioned in said bore below said enlargement of the insulator, and a metal sleeve fast 45 in said bore and backing up the gasket below said enlargement.

In testimony whereof I have signed my name to this specification.

FREDERICK M. FURBER.
